INTEGRAL RISER AND SPRINKLER HEAD

John M. Elek, 5111 Corning Ave.,
Los Angeles, Calif. 90056

Filed Mar. 13, 1975, Ser. No. 558,144

Term of patent 14 years

Int. Cl. D23—01

U.S. Cl. D23—7

Fig. 1.

Fig. 2.

Fig. 3.

FIG. 1 is a side elevational view of an integral riser and sprinkler head showing my new design;

FIG. 2 is a top plan view thereof; and

FIG. 3 is a bottom plan view thereof.

I claim:

The ornamental design for an integral riser and sprinkler head, substantially as shown.
